DESIGN FOR A QUESTION AND ANSWER BOOKLET

Jack B. Riley, Forest Park, Ill., assignor of one-half to Gunnar Anderson, Chicago, Ill.

Application August 5, 1943, Serial No. 110,843

Term of patent 3½ years

To all whom it may concern:

Be it known that I, Jack B. Riley, a citizen of the United States, residing at Forest Park, in the county of Cook and State of Illinois, have invented a new, original, and ornamental Design for a Question and Answer Booklet, of which the following is a specification, reference being had to the accompanying drawing, forming part thereof.

In the drawing—

I claim:

The ornamental design for a question and answer booklet, as shown.
